UNITED STATES PATENT OFFICE.

CHARLES L. DEPOLLIER, OF BROOKLYN, NEW YORK.

WATCH BEZEL AND CRYSTAL.

1,239,467.

Specification of Letters Patent. Patented Sept. 11, 1917.

Application filed May 15, 1917. Serial No. 168,644.

To all whom it may concern:

Be it known that I, CHARLES L. DEPOLLIER, a citizen of the United States, and residing in the borough of Brooklyn of the city of New York, county of Kings, in the State of New York, have invented certain new and useful Improvements in Watch Bezels and Crystals, of which the following is a specification, reference being had to the accompanying drawing, forming a part hereof.

The greatly increased use of wrist-watches by military men and sportsmen developed the necessity for and the production of non-breakable crystals to replace the fragile crystals of glass previously used. Continued use of the unbreakable crystals has shown that they are not only quite susceptible to changes in temperature which result in expansion and contraction, but that in long continued use they are liable to shrinkage, due to the character of the composition of which they are made. In order that such a crystal may be retained permanently in its bezel, notwithstanding expansion and contraction or possible shrinkage, efforts have been made to prevent the loosening of the crystal in the bezel, as by springing the concavo-convex crystal into the bezel so that it shall be always under tension and by making the joint between the crystal and the bezel of such a character that a limited amount of contraction or shrinkage can take place without completely disengaging the crystal from the bezel. It is the object of the present invention to provide a different and more satisfactory means for overcoming the difficulty referred to, and especially means that shall insure under all conditions a tight joint between the crystal and the bezel and shall involve very little expense in the preparation and assemblage of the crystal and bezel. In accordance with the invention, advantage being taken of the toughness of the unbreakable crystal, as distinguished from the brittleness of ordinary glass, provision is made whereby the bezel and the crystal are engaged or interlocked so that the crystal cannot pull away from the bezel. To effect the formation of such a joint in the most convenient manner the bezel is formed, in its inner circumferential edge, with a circumferential groove or recess, to receive, between its upper and lower walls, the edge of the crystal, one or the other or both of the upper and lower members or walls being formed with a rib or projec-

tions to engage the crystal in a manner to prevent the withdrawal from the groove of the bezel. The invention will be more fully explained hereinafter with reference to the accompanying drawing in which it is illustrated and in which,—

Figure 1 is a view in section of a bezel and crystal in which the invention is embodied in a suitable form.

Fig. 2 is a detail view in section of the bezel shown in Fig. 1.

Figs. 3 and 4 are views similar respectively to Figs. 1 and 2, but showing a different embodiment of the invention.

Figs. 5 and 6 are similar views showing a further modification.

Figs. 7 and 8 are respectively an inner edge view and a view in section illustrating a further modification.

The bezel *a* of metal and the crystal *b* of the tough, transparent composition commonly called unbreakable glass, or even of ordinary glass, may be of any desired shape, either round, like the ordinary bezel and crystal, or of any of the more fanciful shapes. In each illustrated embodiment of the invention the inner edge of the bezel is formed with a peripheral groove or recess *c*, which is adapted to receive, between the upper and lower walls or members *a'*, *a''*, the peripheral edge of the crystal. The latter, preferably having the usual concavo-convex form, has an outside diameter greater than the minimum, inside diameter of the bezel. It may or may not be of such diameter as to be maintained in a state of tension when in place in the bezel, it being immaterial, so far as the invention is concerned, whether the crystal be in a state of tension or not. Before the crystal and bezel are assembled, the groove or recess *c* is opened or spread somewhat so as to permit the crystal to be seated easily in the groove, one or both of the members *a'* and *a''* being formed with a rib or projection to engage the crystal positively when the two members are pressed together upon the crystal. The crystal itself, according to its degree of hardness, may or may not be formed on one face or the other or both, as the case may be, with a groove or recess to receive the rib or projection of the bezel. In the embodiment of the invention shown in Figs. 1 and 2 the jaw or member *a''* at the lower side of the groove *c* is formed on its upper face with a rib *a''* to enter a corresponding groove *b''* in

the under side of the crystal b . In the embodiment of the invention shown in Figs. 3 and 4 the upper or outer jaw or member a' is formed with a rib a^4 to enter a corresponding groove b^4 in the upper or outer face of the crystal. In the embodiment of the invention shown in Figs. 5 and 6 the opposing faces of both members a' and a^2 are formed with ribs a^3 and a^4 to enter corresponding grooves b^3 and b^4 formed in the opposite faces of the crystal. If the composition of which the crystal is formed is not so hard as to resist penetration, it may be unnecessary to form the grooves or recesses in the crystal before the bezel and crystal are assembled. The opposed faces of the two members a' , a^2 may be formed with teeth or tooth-like projections, as indicated at a^5 in Figs. 7 and 8, so that when they are pressed toward each other upon the crystal the teeth or tooth-like projections will enter the crystal and effect the positive engagement or interlocking of the bezel and crystal so that the crystal cannot pull away from the bezel as it contracts. It will be understood, of course, that in the embodiments of the invention shown in Figs. 1-6, the two jaws or members of the bezel are pressed toward each other upon the crystal, each jaw forming an abutment against which the crystal is pressed when the other jaw is itself pressed tightly upon the crystal, the rib or ribs in one jaw or the other or both then entering the correspond-

ing groove or grooves in the approximate 35 surface of the crystal.

It will be understood, of course, not only that the invention may be applied to watch-bezels and crystals of different shapes, but that it may be applied also to clocks, compasses and other instruments in which transparent covers are to be secured in place over a dial or otherwise. 40

I claim as my invention:

1. The combination of a crystal and a 45 bezel, the bezel being formed with a groove or recess in its inner edge to receive the edge of the crystal, and one of the opposing walls of the groove or recess being formed with a projection adapted to be forced into 50 engagement with the corresponding face of the crystal to prevent the crystal from being drawn apart from the bezel.

2. The combination of a crystal and a bezel, the crystal being formed with a groove 55 in one face thereof near its edge, the bezel being formed with a groove or recess in its inner edge to receive the edge of the crystal, and one of the opposing walls of the groove or recess being formed with a projecting rib 60 adapted to be forced into engagement with the groove in the corresponding face of the crystal to prevent the crystal from being drawn apart from the bezel.

This specification signed this 11th day of 65 May, A. D. 1917.

CHARLES L. DEPOLLIER.
